Primary Examiner — Rhea Shields(74) *Attorney, Agent, or Firm* — Pearne & Gordon LLP(57) **CLAIM**

The ornamental design for an electric plug receptacle, as shown and described.

DESCRIPTION

FIG. 1 is a front view of an electric plug receptacle according to my new design;

FIG. 2 is a right side view thereof;

FIG. 3 is a left side view thereof;

FIG. 4 is a top view thereof;

FIG. 5 is a bottom view thereof;

FIG. 6 is a first perspective view thereof; and,

FIG. 7 is a second perspective view thereof.

In the drawings, the broken lines are for the purposes of illustrating environment only and form no part of the claimed design.
